LEG REST

William F. Williams, St. Clair Shores, Mich., assignor to Yorna Malcolm, St. Clair Shores, Mich.

Application September 9, 1955, Serial No. 37,874

Term of patent 14 years

(Cl. D15—8)

Fig. 1 is a perspective view of a leg rest showing my design;

Fig. 2 is a perspective view thereof taken on a different angle;

Fig. 3 is a front elevational view of the leg rest; and
Fig. 4 is an enlarged cross-sectional view taken on line
4—4 of Fig. 1.

I claim:

The ornamental design for a leg rest, substantially as shown.
